(57) **CLAIM**

The ornamental design for a chemical release cartridge, as shown and described.

DESCRIPTION

FIG. 1 is a perspective view of an embodiment of a chemical release cartridge according to the present invention.

FIG. 2 is a left side elevation view thereof;

FIG. 3 is a back side elevation view thereof, the front side elevation view being a mirror image thereof;

FIG. 4 is a right side elevation view thereof;

FIG. 5 is a top elevation view thereof; and,

FIG. 6 is a bottom elevation view thereof.

The claimed design is shown fragmented in FIGS. 1-4 to indicate non-specified length.
